US00D682095S

(12) **United States Design Patent**
Cohen et al.

(10) **Patent No.:** US D682,095 S
(45) **Date of Patent:** ** May 14, 2013

(54) **CONTAINER SHROUD**

(71) Applicants: **Erica Eden Cohen**, New York, NY (US); **Nathaniel Giraitis**, New York, NY (US); **William F. Gordon**, Chicago, IL (US); **Kevin Harrity**, Oak Creek, WI (US); **Jonathan N. Mandell**, Gurnee, IL (US); **Nicholas Oxley**, New York, NY (US); **Jacob Palmborg**, Brooklyn, NY (US); **Jessi Pervola**, Brooklyn, NY (US); **Richard Whitehall**, New York, NY (US)

(72) Inventors: **Erica Eden Cohen**, New York, NY (US); **Nathaniel Giraitis**, New York, NY (US); **William F. Gordon**, Chicago, IL (US); **Kevin Harrity**, Oak Creek, WI (US); **Jonathan N. Mandell**, Gurnee, IL (US); **Nicholas Oxley**, New York, NY (US); **Jacob Palmborg**, Brooklyn, NY (US); **Jessi Pervola**, Brooklyn, NY (US); **Richard Whitehall**, New York, NY (US)

(73) Assignee: **S. C. Johnson & Son, Inc.**, Racine, WI (US)

(**) Term: **14 Years**

(21) Appl. No.: **29/436,708**

(22) Filed: **Nov. 8, 2012**

CLAIM

The ornamental design for a container shroud, as shown and described.

DESCRIPTION

FIG. 1 is an isometric view of the top, front and right side of the container shroud showing our new design; FIG. 2 is a front elevational view of FIG. 1; FIG. 3 is a rear elevational view of FIG. 1; FIG. 4 is a right side elevational view of FIG. 1; FIG. 5 is a left side elevational view of FIG. 1; FIG. 6 is a top plan view of FIG. 1; FIG. 7 is a bottom plan view of FIG. 1; FIG. 8 is an isometric view of the top, front and right side of an alternate embodiment of the container shroud showing our new design; FIG. 9 is a front elevational view of FIG. 8; FIG. 10 is a rear elevational view of FIG. 8; FIG. 11 is a right side elevational view of FIG. 8; FIG. 12 is a left side elevational view of FIG. 8; FIG. 13 is a top plan view of FIG. 8; and, FIG. 14 is a bottom plan view of FIG. 8. The broken lines in the drawings depict environmental subject matter only and form no part of the claimed design.
